US0D1040017S

(12) **United States Design Patent** (10) Patent No.: **US D1,040,017 S**
(45) Date of Patent: ** Aug. 27, 2024

(54) **SLIDER**

(71) Applicant: **IDEAL Fastener (Guangdong) Industries Ltd.**, Zhaoqing (CN)

(72) Inventors: **Zongjian Lyu**, Zhaoqing (CN); **Wei Qiu**, Zhaoqing (CN); **Guoliang Qiu**, Zhaoqing (CN); **Franklin Chi Yen Hung**, Zhaoqing (CN)

(**) Term: **15 Years**

(21) Appl. No.: **35/517,880**

(22) Filed: **Jul. 25, 2022**

(80) **Hague Agreement Data**

Int. Filing Date: **Jul. 25, 2022**

Int. Reg. No.: **DM/222490**

Int. Reg. Date: **Jul. 25, 2022**

Int. Reg. Pub. Date: **Jul. 28, 2023**

(30) **Foreign Application Priority Data**

Jan. 28, 2022 (CN) 202230060341.3

(51) **LOC (14) Cl.** **02-07**

(52) **U.S. Cl.**

USPC **D11/221**

(58) **Field of Classification Search**

USPC D2/211, 221; D11/211-221
CPC A43B 1/00; A43B 1/02; A43B 1/04; A43B 3/00; A43B 3/02; A43B 3/06; A43B 3/10; A43B 3/12; A43B 3/14; A43B 5/00; A43B 5/001; A43B 5/008; A43B 5/10; A43B 5/12; A43B 23/00; A43B 23/02; A43B 23/04; A44B 19/04; A44B 19/06; A44B 19/08; A44B 19/26
